GARMENT GRIPPER FOR PRESSING MACHINES

Irving Epstein, Brighton, N. Y.

Application June 13, 1947, Serial No. 754,456

5 Claims. (Cl. 38—12)

1

The present invention relates to the stretching and shaping of garments and particularly to a device for holding a garment on a standard pressing machine while it is being stretched or shaped.

When a garment, particularly a woolen or rayon garment is dyed, it tends to shrink and sometimes to get out of shape. It has to be stretched and re-shaped, therefore, before it is returned to the customer. Heretofore, re-shaping and stretching have been hand operations. The garment is placed on the lower buck or board of a standard steam pressing machine and the operator, reaching across this lower board, takes hold of one side or one end of the garment with one hand and while turning the steam on so that it penetrates the garment, pulls on the garment with his other hand to stretch and re-shape it. To prevent burning the hand with which he is holding the garment, the operator uses ordinarily a protective glove. Of course, the operator can only pull the garment at one point at a time and he has to continuously shift his gripping point and his point of pull to stretch the garment evenly along its whole length and to re-shape it properly. It requires considerable skill to re-shape and stretch properly a long garment, such as a dress or coat, because the operator has to take hold of the garment successively at quite a number of different points along the length of the garment and successively pull at the corresponding opposite points in order to secure the stretching and re-shaping desired. Moreover, this hand operation is time-consuming and expensive.

The primary object of the present invention is to provide a device adapted for use in a pressing machine which will hold a garment along the whole length of one side during stretching or shaping thereof and which will obviate manual holding and the repeated shifting of the manual grip that has been required in prior practice.

Another object of the invention is to provide a garment holder for use on pressing machines, which will grip and hold a garment and leave both of the operator's hands free to stretch or shape the garment.

A further object of the invention is to provide a device for holding a garment in a pressing machine which is so constructed that the power of the machine itself may be exercised through it to hold a garment during stretching or shaping of the garment.

Still another object of the invention is to provide a device which can be inserted between the upper and lower bucks or boards of a standard pressing machine to hold a garment in the ma-

2

chine while the garment is being pulled to stretch or shape it, and which will be of simple construction, relatively cheap, and yet which will be practical to use and have a relatively long life.

Other objects of the invention will be apparent hereinafter from the specification and from the recital of the appended claims.

In the drawings:

Fig. 1 is a perspective view of a conventional steam pressing machine, showing the upper buck or board in raised position and a coat, which is to be stretched or shaped, lying on the lower board or buck, with two of the garment holders of the present invention laid thereon in position to hold the garment when the upper buck is lowered;

Fig. 2 is a fragmentary end view of the pressing machine showing the upper buck lowered to bring and hold the gripping devices in gripping engagement with the garment;

Fig. 3 is a perspective view of a garment holder made according to the preferred embodiment of this invention, part being broken away to show in section the internal structure of the garment holder; and

Fig. 4 is a view, partly in section, showing one step in the manufacture of the garment holder. A garment holder made according to the present invention is preferably made in the form of elongated roll. It is flexible and somewhat elastic or compressible. It may be made in any suitable length and diameter. For the conventional pressing machine it is usual to make the holders in two lengths, one length approximately the length of the lower buck or board of the machine and the other length being slightly greater than the width of this lower buck or board. It has been found that one and an eighth inches makes a suitable diameter for the holders. The garment, which is to be stretched or shaped is placed on the lower buck or board, and a garment holder or holders placed along an edge or edges of the garment. Then the upper buck or board is lowered to cause the garment holder or holders to grip the garment, and while the operator turns on the steam, he pulls the garment along its opposite side or sides to stretch and re-shape it.

Figs. 1 and 2 show how the general structure of holding devices made according to the present invention and how these devices may be used. Here 30 designates the pedestal or stand portion of a conventional steam pressing machine. 31 is the table of this machine, and 32 is the lower buck or board. This is supported above the table 31 by a column or post 33.

The upper buck or board of the machine is denoted at 35. This is mounted upon an arm 36 that is pivoted to the upright at the rear of the machine. 37 denotes a hand grip that is mounted in arms 38 that are secured by bolts 39 to the upper buck 35. This hand grip can be grasped to lower the upper buck and to increase the pressure thereon. Foot pedals 40, 41 and 42 are provided in the base of the machine to control the steam and the pressure on the upper buck when it is lowered.

To stretch a coat, such as shown at G, for instance, the operator first lays the coat over the lower buck 32. Then he lays one of my garment grips 10 along the length of the garment at one edge thereof and another shorter grip 10' along one end of the garment, for instance, the bottom end, as shown in Fig. 1. The garment holders are elongated flexible rolls which in normal, released position are substantially cylindrical in shape. When garment and garment holders are in position, the operator lowers the upper buck 35, and by pressing the appropriate foot pedal applies pressure to the garment grips 10 and 10' to hold the garment G securely between the upper and lower bucks. At the same time by pressing the appropriate foot pedal he turns on the steam to steam the garment as he holds it. Then with his two hands he can pull the free edge of the garment sidewise or lengthwise to stretch and shape the same. By readjusting the garment and the grips he can stretch and re-shape the garment until it has the desired size and shape.

The grips or garment holders of the present invention, leave the operator with both hands free to pull and stretch the garment. Moreover, they allow the gripping force of the press itself to be exerted to hold the garment while it is being stretched and shaped. Further, the grips of the present invention permit of holding the garment along the whole of its length at one time so that the operator can pull and stretch the garment along its whole length simultaneously. This is a very appreciable advantage over the old method in which the operator was only able to hold the garment with one hand at one place along its length and pull the garment at the opposite side to stretch the same. The operator had then to reshift his grip repeatedly in order to stretch the garment and shape it as desired. Further than this, with the old method, the operator was not able to hold the garment as securely as it can be held by the pressing machine so that he was not able to exert as much pulling pressure. By using two or more grips simultaneously, as shown in Fig. 1, the operator is able to stretch the garment longitudinally and laterally in a single set-up, which again saves time.

A preferred construction for the garment holders of this invention is shown in Figs. 3 and 4. Here the garment holder or roll 10 comprises an outer covering 11 made of drill or other suitable cotton or linen cloth and a filler 12.

The material of the outside envelope 11 is preferably cut on the bias to prevent its stretching and to hold its shape. The edges and ends of the envelope are sewed together, the stitching along the length of the roll being indicated at 15 and at one end at 16.

The filler is preferably a quilted material like that ordinarily employed for the covering of pressing machines, which is rolled into a spiral roll that is inserted into the envelope or casing 11. This filler may consist of elongated rolls of cloth 13 filled with cotton and sewed together as indi-

cated at 14. This gives strength and resilience to the filler and the filler will not compact and become hard as would cotton batting or a simple cotton stuffing.

To secure the necessary firmness in the roll with resilience, the roll of stuffing or filler 12 used is of a normal expanded diameter considerably in excess of the diameter of the filled roll.

To get the filler into its casing 11 a piece of brass tubing 20 having a flared end 21 may be used. The casing material 11, having been sewed together to form the envelope, is telescoped onto the outside of this tube 20 and the filler 12 is fed into the tube through the flared end 21 thereof. As the filler enters the casing 11, the casing is fed off of the tube, and when the casing has been completely filled the open end thereof is sewed around the filler.

The structure of the garment holders described gives them resilience and long life. They compress to oval shape under pressure of the upper buck, as shown at the right in Fig. 2, thus providing a broad gripping surface, but when the pressure is released, they take their substantially cylindrical shapes again.

While the invention has been illustrated and described particularly with reference to the stretching and shaping of garments, it will be understood that it may be employed in connection with the stretching of various articles made of fabrics. Thus it has been used for shaping and stretching slip-covers, drapes and other household articles. It is not limited to the stretching and shaping of articles of personal wear.

While the invention has been illustrated in connection with the use of two garment holders simultaneously, it will be understood that one or more may be used at a time as desired. It will further be understood that while the invention has been described in connection with a particular embodiment thereof, it is capable of further modification, and this application is intended to cover any variations, uses, or adaptations of the invention following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. A device for use in holding work in a platen-type garment-pressing machine having an upper and a lower buck, said device comprising an elongated, generally-cylindrical, resilient roll, said device being adapted to be placed upon a garment along one edge thereof, after the garment has been disposed on the lower buck, so that when the upper buck is pressed into engagement with the device, the device will clamp the garment with gripping engagement localized along said edge of the garment.

2. A device for use in holding work in a platen-type garment-pressing machine having upper and lower bucks, said device comprising a completely closed fabric envelope, and a resilient filler therefor, said device being adapted to be placed upon a garment along one edge thereof, after the garment has been disposed on the lower buck, so that when the upper buck is pressed into engagement with the device, the device will clamp the garment with a gripping engagement localized along said edge of the garment.

3. A device for use in holding work in a platen-type garment-pressing machine having upper and lower bucks, said device comprising an elongated, resilient roll which comprises an elongated envelope and a cotton filler therefor, said envelope being completely closed, said device being adapted to be placed upon a garment along one edge thereof, after the garment has been disposed on the lower buck, so that when the upper buck is pressed into engagement with the device, the device will clamp the garment with a gripping engagement localized along said edge of the garment.

4. A device for use in holding work in a platen-type garment-pressing machine having upper and lower bucks, said device comprising an elongated, resilient roll which comprises an elongated fabric envelope and a quilted cotton filler therefor, said envelope being completely closed, and said filler being of a normal diameter greater than the internal diameter of the envelope, said device being adapted to be placed upon a garment along one edge thereof, after the garment has been disposed on the lower buck, so that when the upper buck is pressed into engagement with the device, the device will clamp the garment with a gripping engagement localized along said edge of the garment.

5. A device for use in holding work in a platen-type garment-pressing machine having upper and lower bucks, said device comprising a completely closed fabric envelope, the material of which is

cut on the bias, and a filler for said envelope made of a quilted material rolled in a spiral roll, the diameter of said spiral roll being normally greater than the internal diameter of the envelope, said device being adapted to be placed upon a garment along one edge thereof, after the garment has been disposed on the lower buck, so that when the upper buck is pressed into engagement with the device, the device will clamp the garment with a gripping engagement localized along said edge of the garment.
